United States Patent Office.

J. D. DE TURK, OF EXETER, PENNSYLVANIA.

Letters Patent No. 75,669, dated March 17, 1868.

IMPROVEMENT IN CULTIVATOR-TEETH.

The Schedule referred to in these Letters Patent and making part of the same.

TO ALL WHOM IT MAY CONCERN:

Be it known that I, J. D. DE TURK, of the township of Exeter, in the county of Berks, and State of Pennsylvania, have invented a new and useful Improvement on a Cultivator-Tooth; and I do hereby declare that the following is a full, clear, and exact description of the construction and operation of the same, reference being had to the annexed drawings, making a part of this specification, in which—

Figure 1 is a front view.

Figure 2 is a side view.

Figure 3 is a side view with the cap out of gear or thrown open.

Figure 4 is a top view of cap, or my improvement.

This instrument or improvement is constructed of cast or wrought iron, or other metal.

To enable others to make and use my invention or improvement, I will proceed to describe its construction or operation.

I construct my improved cultivator-tooth of cast iron, but the same may be made of any of the baser metals. An ordinary cultivator-tooth is constructed with a flattened neck, as represented in figs. 1 and 3, letter e. Over the neck I place a cast-iron cap, as represented by letter A in all the figures, 1, 2, 3, and 4. The cap is fastened to the neck by the hinge or screw-bolt, represented by letter a in figs. 1, 2, and 3, and the wooden pin or key represented in fig. 2, letter c, the same to be attached to the beam of the cultivator by a bolt passing through a hole in the cap at letter d. Letter b, in all the figures, represents a steadyng-tip or teat on top of the cap. The cap being attached to the wooden beam, and the tooth attached to the cap, should the tooth come in contact with a hard or unyielding substance, the wooden pin or key at c will break and save the tooth.

What I claim as my invention or improvement, and desire to secure by Letters Patent, is—

The cap, represented in figs. 1, 2, 3, and 4, intended to be fastened to the cultivator-beam, into which the tooth is to be inserted, and fastened by the iron hinge-bolt a, figs. 1, 2, and 3, and the wooden pin or key at letter c, figs. 2 and 3, by the use of which the breaking of the tooth can be avoided.
